ATTORNEYS.

UNITED STATES PATENT OFFICE.

AARON N. DUKES, OF PERU, INDIANA.

DESIGN FOR A DRIP-CUP.

SPECIFICATION forming part of Design No. 26,926, dated April 20, 1897.

Application filed November 10, 1896. Serial No. 611,679. Term of patent 7 years.

To all whom it may concern:

Be it known that I, AARON N. DUKES, of Peru, in the county of Miami and State of Indiana, have invented and produced a new and useful Design for a Drip-Cup, of which the following is a full, clear, and exact description.

Reference is to be had to the accompanying drawings, forming a part of this specification, in which similar characters of reference indicate corresponding parts in both the figures.

Figure 1 represents a perspective view of a drip-cup embodying my new design, and Fig. 2 is a transverse vertical section of the same.

The leading feature of my design consists of the approximately semioval-shaped body *a*, the upwardly-projecting arms *b* at opposite sides of the body, and the laterally-projecting lugs *c* at the upper ends of the said arms. 20

A minor feature of the design is the taper of the arms *b*.

I claim—

The design for a drip-cup herein shown and described.

AARON N. DUKES.
